UNITED STATES PATENT OFFICE.

AUGUST K. BRAUN, OF NEW YORK, N. Y.

ELECTRIC MOTOR.

SPECIFICATION forming part of Letters Patent No. 737,553, dated August 25, 1903.

Application filed July 3, 1903. Serial No. 164,181. (No model.)

To all whom it may concern:

Be it known that I, AUGUST K. BRAUN, a citizen of the United States of America, and a resident of New York, in the county and 5 State of New York, have invented a certain new and useful Electric Motor, of which the following is a specification.

My invention relates to devices wherein the application of electromagnetism to the 10 propulsion of machinery is utilized, and particularly to that class of electric motors in which an armature is attracted by the energization of an electromagnet; and it has for its object the provision of an apparatus of 15 the kind set forth simple in construction, inexpensive to manufacture, and which operates rapidly and efficiently in practical use.

To attain the desired end, this my invention consists in the construction, arrangement, and operation of parts herein set forth.

In order to enable my invention to be fully understood, I will proceed to explain the same by reference to the drawings which accompany and form a part of this specification, 25 in which—

Figure 1 represents a plan view of a small motor embodying my invention, and Fig. 2 is a side elevation of the same.

Like letters of reference indicate like parts 30 in both views.

Referring particularly to the drawings, A denotes the base of my motor, which consists of a hollow or box-like structure constructed to contain an electric battery, the same being preferably made of a truncated pyramid shape and having the sides lined off in imitation of brickwork in order to represent the solid bed of a power-motor. The interior of the base A may contain an electric battery 35 B, the electrodes of which are respectively connected with the post a', located on the exterior of the base A, and the wire b, extending upwardly through the base and being electrically connected with the electromagnets C C' and C² C³. The electromagnet C³ is connected with the insulated spring-finger D, and the electromagnet C' is electrically connected with the insulated spring-finger D'. The said electromagnets are supported by a preferably integral metal frame 40 E, provided with oppositely-disposed bearings e² and with legs e and a projecting

arm E', provided with vertical lugs e³, in which is journaled a shaft F, carrying a pulley f, fly-wheel f', pin or projection f², and 55 a crank-arm f³. The reciprocating armature G is sustained by a rod g, passing through the bearings e², which rod g is connected by a link g² with the crank-arm f³ of the shaft F. The spring-fingers D D' are supported by an 60 insulated plate d, secured to the frame E. The switch a is electrically connected with the frame E of my apparatus, preferably by means of a wire running from the said frame to the switch a. 65

In operation upon the switch a being closed or put in electric connection with the post a' the electric current will pass through one pair of electromagnets—say the magnets C C'—thence through wire b² to the insulated 70 spring-finger D', which may at this moment be in electric connection with the rotatable pin or projection f², which revolves between and alternately engages the spring-fingers D and D'. The armature being in a median position between the two pairs of electromagnets is now attracted by the electromagnets 75 C C' and upon approaching the same causes the projection to pass away from the finger D', thus breaking the circuit, and the said 80 projection being carried farther around by the momentum of the fly-wheel a new circuit will be established through the wires b b' with the electromagnets C² C³ and spring-finger D, the armature-rod in the meantime 85 having been moved by the crank-arm f³ and link g² to its median position again. The armature is now attracted to the electromagnets C² C³, and the shaft F is caused to rotate by the reciprocal movement of the armature G. 90

As it is evident that many changes in the construction, form, proportion, and relative arrangement of parts might be resorted to without departing from the spirit and scope 95 of my invention, I would have it understood that I do not restrict myself to the particular construction and arrangement of parts shown and described, but that such changes and equivalents may be substituted therefor, 100 and that

What I claim as my invention is—

1. In combination, two pairs of oppositely-disposed electromagnets, a reciprocating ar-

mature located therebetween and sustained by a rod passing through the magnet support or frame, a support for a shaft, two insulated springs, a projection on the shaft to engage 5 each spring alternately, a crank-arm on said shaft, and a link intermediate the crank-arm and the armature-rod, and a hollow base, a switch located exteriorly of the same, and a battery contained within the base.

10 2. In combination, two pairs of oppositely-disposed electromagnets, a reciprocating armature located therebetween and sustained by a rod passing through the magnet support or frame, a projecting arm thereof forming a 15 support for a shaft, two insulated springs, a projection on the shaft to engage each spring alternately, a crank-arm on said shaft, and a link intermediate the crank-arm and armature-rod, the said frame also serving to hold

the magnet and shaft rigidly in position, and 20 two terminals of an electric circuit, an electric connection from one terminal through one coil to one of said fingers and an electric connection from the said terminal through the other coil to the other spring-finger, and 25 also an electric connection between the shaft projection and the second terminal, and a hollow base, a switch located exteriorly of the same, and a battery contained within the base.

In testimony of the foregoing specification I do hereby sign the same, in the city of New York, county and State of New York, this 29th day of June, A. D. 1903.

AUGUST K. BRAUN.
